UNITED STATES PATENT OFFICE.

WILLIAM T. McGINNIS, OF PRINCEVILLE, ILLINOIS.

PRINTING APPLIANCE.

Application filed March 12, 1926. Serial No. 94,156.

This invention has reference to certain new and useful improvements in printing appliances, and it has for its principal object to provide a new and more efficient 5 means for locking a top or type-plate to the base or base member or members, which upon being locked together are set up in a chase preparatory to printing.

Base members to which the top or type- 10 plates are connected have been constructed heretofore so as to coact with a complementary member cast on the top or type-plate which prevented movement of the top or type-plate on the base members in two directions only; i. e. their separation bodily and sliding movement in one direction. Such an assembly, when the base members and top or type-plates are held in a chase requires the introduction of slugs together 15 with the ordinary and regular furniture fillers to hold the top plates securely and against movement in directions not provided for by the locking means connecting the base members and the top or type-plates. Owing 20 to the top or type-plates being cast very shallow, the use of the slugs, unless very carefully placed are type high and more or less smear the printed surface which becomes 25 very objectionable, especially when cuts of persons or things appear on the cast surface 30 of the top or type-plates.

My improved locking means between the base members and the top or type-plate obviates any and all of these objections and 35 insures a sufficient securing of the top or type-plate to the base or base members against movement in all directions with relation to each other and simplifies the securing of the base member or members to the top 40 or type-plates within a chase.

That the invention may be more fully understood, reference is had to the accompanying drawing forming a part of the present description and illustrating a preferred 45 embodiment of the invention, in which—

Fig. 1 is a top plan view showing the manner and form of locking a top or type-plate within a chase without the necessity of using slugs;

Fig. 2 is a top plan view of a top or type-plate and base member or members as they

appear when locked together, the top or type-plate broken away and dotted and full lines showing my improved locking means;

Fig. 3 is a cross section in elevation, as 55 the same would appear if taken on the line 3-3, Figure 2.

Fig. 4 is a perspective view of a base member constructed according to my invention, and 60

Fig. 5 is a perspective view broken in two showing a top or type-plate cast, according to my invention.

Like characters of reference denote corresponding parts throughout the figures. 65

In Figure 1 I have illustrated a top or type plate 1 locked to a base member or members therebeneath, not shown, and these elements locked in a chase A through and by means of the usual and ordinary furniture fillers a and b and the usual and well known quoins c. The chase, furniture fillers and quoins form no part of the present invention.

The top or type-plate 1 is formed in the 75 usual manner with type face or other material, such as figures, portraits and the like, not shown, and with the spaced longitudinally disposed ribs or webs 2 on the underneath side thereof which form rests for the top or type-plate on a base member or members 3, also cast on the underneath side of the top or type-plates 1 are one or more ribs or webs 4, somewhat like the ribs or webs 2, except that they are preferably wedge like in cross

section which are adapted to coact with wedge surfaces 5 and wedge like ribs or webs 6 on the base member or members 3. The ribs or webs 4 and the wedge surfaces 5 and the ribs or webs 6 provide complementary locking members between the top or type-plate and base member or members which are adapted to have a sliding locking relation and prevent bodily separation of the top or type-plate from the base member or members and prevent slidable separation thereof in one direction, preferably cross-wise between such parts. 80

Thus far the structure of the top or type- 85 plates and the base member or members is substantially what is and has been used. It 90 being understood that the ribs or webs 2 and

4 on the top or type-plates extend, in a direction what I shall choose to designate, longitudinally of the top or type-plates and naturally the wedge surfaces 5 and ribs or webs 6 5 on the base member or members are disposed in a like direction thereon, regardless of their size. This is evidenced by an examination of Figures 2, 3 and 4.

Referring now to my improved locking 10 means between the base member or members and top or type-plates, I construct the base members, which are usually placed coincident with the opposite ends of a top or type-plate and coinciding with preferably corresponding corners at opposite ends thereof with an angularly disposed lug 7 of preferably triangular shape with its inside edge or face wedge like, as at 8, see Figure 4. The top or type-plates 1 are provided on their 15 underneath side and at preferably corresponding corners at each end, see Figure 5, with preferably triangularly formed recesses or seats 9, the inside walls of which are tapered or wedge shaped, as at 10. These recesses or seats 9 in size and shape conform substantially to the lugs 7 on the base member or members and in relation to which they overlie when the base members and top or type-plates are in locked relation; such locking 20 relation being brought about by the sliding relation between the wedge like faces 8 of the lugs 7 with the tapered or wedge like walls 10 of the recesses or seats 9 in the top or type-plates. To bring the complementary locking parts of the base members and a top or type-plate into locking relation, the base members at the opposite ends for the top or type-plate are moved into position towards the ends of each end of said top or type-plate. 25 By examining Figure 4, it will be observed that the lugs 7 are so placed on the base members, that their locking faces 8 are opposite 30 5, although inclined from, and face the wedge shaped locking faces of the ribs or webs 6 thereon. It should now be obvious that with such disposition of the locking members on a base member that when a top or type-plate is locked thereto, said plate is held between base members at opposite ends against longitudinal movement in either direction; against

sidewise movement in either direction and against bodily separation from and towards each other. It is being assumed, of course, the statement is predicated on the locked base members and a top or type-plate being held within a chase, somewhat as shown in Figure 1.

What I claim is:—

1. In a printing appliance, a base member for a top or type-plate comprising a unitary structure having locking members on its acting face one of which has its engaging face bearing obliquely to the other and adapted for locking relation with complementary parts on such a top or type-plate to hold the latter against sliding movement in longitudinal and transverse directions and against bodily movement toward and from said locking members. 60

2. In a printing appliance, in combination, 70 a top or type-plate provided with spaced parallel locking ribs extending between opposite edges and with locking surfaces at oppositely disposed corners of one edge of said plate, base members for the locking surface ends of said top or type-plate, each member provided with locking ribs complementary to the locking rib of said top or type-plate and with spaced locking lugs 75 complementary to the corner locking surfaces of said top or type plate. 80

3. In a printing appliance, a top or type-plate provided on its underside with a wedge shaped locking rib extending between opposite edges and with recesses at certain of its corners having an angularly disposed locking wall, and base members for said plate having spaced portions complementary to the locking rib and angularly disposed locking 85 walls on said plate. 90

4. An article for use in printing, comprising a base member provided with a wedge shaped locking rib disposed between opposite edges thereof and with a triangularly disposed lug at one corner having a wedge shape locking face adapted to secure a plate having complementary elements. 95

In witness whereof, I have hereunto affixed my hand this 10th day of March, 1926.

WILLIAM T. McGINNIS.
